UNITED STATES PATENT OFFICE

JAMES GARTH MITCHELL, OF BELFAST, NORTHERN IRELAND

SPRING HINGE

Application filed July 6, 1931, Serial No. 549,069, and in Great Britain July 15, 1930.

This invention has for its object to provide improved spring hinges for doors and the like, wherein the controlling spring or springs is or are made readily accessible and capable of being removed and replaced without dismounting the door.

In the two accompanying sheets of explanatory drawings:—

Figure 1 is a part sectional front elevation showing one application of the invention to a double acting spring door hinge, and Figure 2 is an end view of the hinge.

Figure 3 is a plan of the hinge, and Figure 4 a sectional plan on the line 1.2. Figure 1.

Figure 5 is a plan showing one application of the invention to a single acting hinge.

Figures 6 and 7 are opposite end views of this hinge, and Figure 8 is a front elevation 20 of the same.

In carrying the invention into effect as shown in Figures 1-4, I employ a body part *a* and a pair of plates *b*. Each plate is adapted to be attached by screws or other fastenings to one edge of a door *c* or its frame *d*. Also each plate *b* is formed with a plurality of knuckles *n*, and along each end the body part *a* is formed with knuckles *p*. It will be noticed that the knuckles at one end of the 25 body part alternate with those at the other end. Transversely across the body, which has both ends exposed, opposite each knuckle notch is formed a cylindrical chamber *f*. Each chamber at one end is intersected by the 30 knuckle notch, and at the other end is open. Into each chamber are inserted a thimble *g* which can bear against a flat face on the adjacent knuckle, a helical spring *h*, and a hollow plug *i* which is screwed into the open end 35 of the chamber for holding the spring and thimble in position. The outer end of the plug is notched transversely for engagement by a screw driver, or is otherwise adapted for 40 convenient manipulation when placing the plug in position or withdrawing it.

The plate knuckles are attached to the body part by pivot pins *j*, inserted endwise through the assembled parts, so that the plates and body part lie in parallel planes when the hinge is in a closed position, the

end portions of the pins being secured by screw threads as shown. In the example illustrated, each plate is attached to the body part by three coaxial pins, arranged so that springs lie between the adjacent ends of each pair.

When the door is opened in one direction the plate attached to the door moves relatively to the body part, and when the door is moved in the other direction this plate and the body part move together relatively to the plate attached to the frame. It is desirable to prevent relative movement of the body part and one of the plates in each direction of movement. I therefore provide in a notch in the upper end, or lower end, or both, of the body part, a slidible locking piece *k* which can engage a recess *l* in either of the adjacent knuckles of the plates, the portion of the knuckle near the recess serving as a cam for moving the locking piece. Looking at Figure 3, if the door is moved to the right, the right hand knuckle will move the locking piece into engagement with the left hand knuckle, and so prevent movement of the body part relatively to the plate attached to the frame. In the position shown the locking piece engages the right hand knuckle, and if the door were moved to the left, the left hand knuckle would hold the locking piece in this position thereby preventing relative movement between the body part and the plate attached to the door.

The essential feature of my present invention resides in the arrangement of the spring chambers, so that each spring is readily accessible. In the event of a spring breaking it can easily be replaced by removing the end plug, without detaching the hinge from the door.

In the application of the invention to single acting hinges as shown in Figures 5-8, a pair of main parts are used. One of them consists of a plate *m* which at one edge is formed with knuckles *n*. The other consists of a body part *o* formed with knuckles *p*, and also with attachment lugs *q*. Within the body part is formed a chamber containing a thimble *r* which can co-operate with one of the knuckles *n*. The thimble is acted on by

a strong spring *t*, and the spring is held in position by a hollow plug *u*. The knuckles *n*, *p* are interconnected by a single pivot pin *s*.

The part *m* is attached by screws *v* to, for example, the frame *w* of the door, and the part *o* is attached by screws *x* to the door itself, as shown in Figure 1. The mode of attachment of the hinge to the door is such as leaves the end containing the plug *u* freely accessible. If at any time it is required to replace the spring, this can be done without dismounting the door.

While only one chamber and spring are shown in the example above described, the body part may, if desired, be made wide enough to accommodate two or more of such chambers and springs, but in all cases the end of the body containing the plugs *u* is exposed so as to give access to the springs without disturbing the connection of the hinge with the door.

While primarily intended for doors, the hinges above described may be applied to other analogous uses. Also the invention is not limited to the example illustrated as subordinate details may be varied to suit different requirements.

Having thus described my invention what I claim as new and desire to secure by Letters Patent is:

1. In spring hinges, the combination of knuckled and hingedly connected parts arranged to lie in parallel planes when in a closed position, a spring containing chamber arranged transversely across one of the said parts which has both ends exposed, so that one end of the chamber is accessible for the insertion of a spring, while the other end of the chamber is situated adjacent to a knuckle on the other hinge part, a thimble in said chamber acting on the said knuckle, a helical controlling spring in the chamber acting on the thimble, and a removable closure device inserted in the accessible end of the chamber so as to form a seating for said spring, substantially as described.

2. In spring hinges, the combination of knuckled and hingedly connected parts arranged to lie in parallel planes when in a closed position, spring containing chambers arranged transversely across one of the said parts, which have both ends exposed, a thimble in one end of each chamber bearing against a knuckle on the other part, a helical controlling spring in each chamber acting at one end on the thimble, a screwed plug in the other end of each chamber acting on the other end of the spring, substantially as described.

3. In spring hinges of the kind specified, the combination of a body part formed with spring containing chambers lying across the body part which have both ends exposed, so that one end of the chamber is accessible for the insertion or removal of the spring while the other end of the chamber is situated ad-

jacent to a knuckle, removable closure devices at the outer ends of the chambers a helical spring in each chamber, and knuckled plates pivotally attached to opposite ends of the body part so as to lie in planes parallel to the plane of the latter when in a closed position, the knuckles on either plate being arranged to alternate with those on the other plate, substantially as described.

4. In spring hinges as claimed in claim 3, the combination with the body part, of a slideable locking piece for interengaging either plate with the body part when relative movement occurs between the body part and the other plate, each plate being adapted to be engaged by one end of the locking piece and to serve as a cam for moving the said piece, substantially as described.

In testimony whereof I have signed my name to this specification.

JAMES GARTH MITCHELL.
